UNITED STATES PATENT OFFICE.

DANIEL MEYER, OF PARIS, FRANCE.

INCANDESCENT GAS-BURNER.

SPECIFICATION forming part of Letters Patent No. 597,011, dated January 11, 1898.

Application filed May 15, 1897. Serial No. 636,791. (No model.) Patented in France November 19, 1896, No. 261,415; in Belgium February 9, 1897, No. 126,270; in Luxembourg February 9, 1897, No. 2,753, and in England April 6, 1897, No. 8,759.

To all whom it may concern:

Be it known that I, DANIEL MEYER, a citizen of the Republic of Switzerland, residing at Paris, in the Republic of France, have invented certain new and useful Improvements 5 in Incandescent Gas-Burners, (for which I have obtained patents in France, No. 261,415, dated November 19, 1896; in Belgium, No. 126,270, dated February 9, 1897; in Luxembourg, No. 2,753, dated February 9, 1897, and in England, No. 8,759, dated April 6, 1897;) and I do hereby declare the following to be a full, clear, and exact description of the invention, such as will enable others skilled in the 15 art to which it appertains to make and use the same.

This invention has for its object an improved burner for incandescent lamps, which consists more particularly in a novel method 20 of construction and arrangement of the incandescent "mantle," in which strings of beads made of material capable of the required incandescence are used, such mantles not being liable to breakage, as in the mantles 25 ordinarily used.

By the mixture of suitable chemical substances of the well-known kinds a compact incandescent material is obtained, which is dried and hardened and formed into particles 30 of any suitable shape, such as spheres, cubes, cylinders, pyramids, or in clusters or bunches, like grapes, tulips, and the like, of any suitable dimensions from about one millimeter. The particles of grains thus produced are traversed centrally or at one side by one or more metallic or other suitable wires or threads, by 35 which strings or rows of them are formed. The several strings or rows may be combined either one above the other or side by side— 40 that is to say, horizontally or vertically—to form the mantle, or the incandescent grains may be arranged in zigzag form, alternate squares, or the like, or in some cases the metallic or other wires connecting them may 45 be omitted, the grains being then connected or attached together by suitable means before being finally mounted upon the burner.

The accompanying drawings are in illustration of my invention.

50 Figure 1 represents a vertical section of a burner provided with an incandescent mantle

and embodying my invention. Fig. 2 represents a cross-section on the line 11, looking downward. Fig. 3 represents a detail view, in rear elevation, of the support for the said 55 mantle and its attaching devices; and Fig. 4 represents a vertical section through one side of the mantle and a part of its ring and support.

Around a metal ring *a* are arranged a number—twelve, for instance—of hooks *b* at equal distances apart, and upon this ring *a* is also provided a bracket *c*, in which a stem *d*, carrying a ring or top *e*, is fixed at the required height by a screw. The rows or strings *f* consist each of nine (in the drawings) beads or particles of the incandescent material, five rows of larger ones and four rows of smaller ones being shown, threaded upon a double wire of metal or other suitable material forming a loop at one end *g*, Fig. 4. To form the mantle the loops *g* are fitted over the hooks *b*, and the other ends of the wire are then fastened around the upper ring *e*.

The gallery *h* is supported directly upon the shoulder *i* of the Bunsen burner, which is provided at the part below the gallery with four openings *j*, which I make as high as possible instead of the limited height ordinarily used. These openings are fitted inside with 80 wire-gauze, and in the lower part of the Bunsen burner is screwed a gas-jet communicating with the gas-supply pipe and pierced with five small holes for the passage of the gas. The object of this arrangement is to allow the 85 admission to the burner of a much larger volume of air than is the case in ordinary burners of the kind.

The burner thus made is much stronger and more durable than all heretofore-existing forms of incandescent burners. Moreover, it wears away much less easily and may be used for many years without requiring any repair. It can be readily carried without injury and it can be easily used and lighted in 95 the ordinary way.

Having now particularly described and ascertained the nature of my said invention and in what manner the same is to be performed, I declare that what I claim is—

1. An incandescent mantle for a burner consisting of a number of wires arranged in

the form of a frustum of a cone and a series of perforated beads strung on each of the wires, in combination with a burner having slot *j* extending nearly its whole length substantially as set forth.

2. An incandescent mantle for a burner, consisting of a number of wires arranged in the form of a frustum of a cone and a series of perforated beads strung on each of the wires substantially as set forth.

3. An incandescent mantle for a burner, consisting of a number of wires arranged in tubular form and a series of perforated beads strung on each of the wires substantially as set forth.

4. An incandescent mantle in the form of a frustum of a cone consisting of a number

wires arranged in parallel lines and fastened at both ends and a series of non-metallic particles attached to each of these wires at various points along its length for the purpose set forth.

5. An incandescent mantle in tubular form consisting of a number of longitudinal parallel wires and a series of non-metallic particles attached to each of the wires at various points of its length substantially as set forth.

In testimony whereof I affix my signature in presence of two witnesses.

DANIEL MEYER.
